UNITED STATES PATENT OFFICE.

JOHN A. STEELSMITH, OF WICHITA FALLS, TEXAS.

DEVICE FOR ADJUSTING SIEVES IN THRESHING-MACHINES.

No. 806,508.

Specification of Letters Patent.

Patented Dec. 5, 1905.

Application filed March 8, 1904. Serial No. 196,269.

To all whom it may concern:

Be it known that I, JOHN A. STEELSMITH, a citizen of the United States, and a resident of Wichita Falls, in the county of Wichita 5 and State of Texas, have invented a new and Improved Device for Adjusting Sieves in Threshing-Machines, of which the following is a full, clear, and exact description.

The purpose of the invention is to provide 10 a very simple, economic, and effective mechanism for adjusting the sieves in a threshing-machine either up or down at either end of the sieve-frame, which mechanism is capable of being operated by one individual from the 15 outside of the machine, and, further, to so construct the device that where the motion of the machine is not too rapid the adjustment of the sieves can be made while the machine is in motion.

20 Another purpose of the invention is in the construction of the mechanism to employ rods which pass directly across the shoe, acting as supports for the sieve or sieves, and by this means of adjustment much of the operator's time is saved and the convenience with 25 which the adjustment can be made enables the operator to change the position of the sieve a great many times and thereby better the quality of the work, which could not be 30 done without considerable loss of time under the ordinary mode of making such adjustments.

The invention consists in the novel construction and combination of the several 35 parts, as will be hereinafter fully set forth, and pointed out in the claim.

Reference is to be had to the accompanying drawings, forming a part of this specification, in which similar characters of reference 40 indicate corresponding parts in all the figures.

Figure 1 is a side elevation of the shoe having the improved adjusting device applied, the hand-wheel and lock-nuts being removed and the hand-wheel being shown in dotted 45 lines, the said view representing that portion of the shoe at which the operator generally stands. Fig. 2 is a front elevation of one of the adjusting devices adapted to be located on that side of the shoe at which the operator 50 stands, the said adjusting device being in complete form. Fig. 3 is a longitudinal vertical section taken practically on the line 3-3 of Fig. 4 showing two sieves in position, one in positive and the other in dotted lines; and 55 Fig. 4 is a plan view of the shoe, the sieve, and

applied adjusting devices. Fig. 5 is a transverse vertical section taken on the line 5-5 of Fig. 1. Fig. 6 is an inner face view of a locking-plate employed in connection with the adjusting devices, and Fig. 7 is an end view of the said plate.

A represents the shoe for the threshing-machine, and B a sieve for the same, one or more of which may be employed. At opposite sides of the deeper end of the shoe vertical and transversely registering slots 10 are employed, as is shown in Fig. 3, and in corresponding relation at the shallower end of the shoe shorter vertical slots 11 are formed. The shoe is provided with the usual hinging-supports 12.

An adjusting-plate C is secured to the outer face of the shoe at the slots 10 and 11, and said adjusting-plates are of substantially the same construction, being provided with 75 a central longitudinal slot 13, arranged to coincide with the slots 10 and 11 in the shoe. Each adjusting-plate C is of angular construction, as is shown in Fig. 4, comprising a body 14, in which the aforesaid slot 13 is 80 made, which body is adapted to lie close to the body of the shoe, and a rack 15, which is longitudinally and vertically formed or secured on the outer face of the body 14, preferably at its right-hand edge, according to the 85 reading of the drawing, the teeth of the rack facing toward the center of the body, as is shown in Figs. 1 and 2. In the further construction of one set of said adjusting-plates at the opposite side edge of the body 14 a depression 18 is made in the outer face of the 90 plate, and on this depressed surface a scale c is produced, reading, for example, from "1" to "9," and the scales on said latter adjusting-plates C read relative to each other. The 95 adjusting-plates C are secured to the shoe by bolts 19 or their equivalents.

In the further construction of each adjusting-plate C ribs or corrugations 16 are produced upon its outer face, extending transversely preferably from the rack 15 to the depression 18, as is shown in Fig. 1, and from the top to the bottom of the body 14 of the said adjusting-plate.

A locking-plate C' is employed in connection with each adjusting-plate C, one of which locking-plate is shown in detail in Figs. 6 and 7. The locking-plate C' is provided with corrugations or ribs 20 on its inner face at its upper portion adapted to engage with 105

110

the corrugations on the body 14 of an adjusting-plate, and at the central portion of the corrugated or ribbed surface 20 an aperture 22 is located, while other apertures 22^a are located in longitudinal alinement in the lower or plain face of the locking-plate, as is shown in Fig. 3. At one side of the locking-plate a pointer 22^b is mounted adapted as said locking-plate is moved to travel over the scale-depression 18, as is shown in Fig. 1.

Two lugs 21 are formed upon the ribbed or corrugated face of the locking-plate C', which lugs have sliding movement in the slots 10 and 11 of the shoe and the slots 13 of the adjusting-plate, in connection with which the locking-plate is employed. These lugs 21 serve to guide a locking-plate in its movement upon an adjusting-plate.

The sieve B is shown supported at the deeper end of the shoe A by means of a rod D, which rod passes through the slots 10 in the shoe and through the slots 13 in the adjusting-plates C.

Adjacent to each end of the supporting-rod D, outside of the shoe, a polygonal section 23^a is formed, and on one polygonal section of the said supporting-rod D a pinion 23 is mounted, having integral therewith or attached thereto a hand-wheel 24, by means of which the rod D is turned, and upon the opposite polygonal section 23^a of the said sieve-supporting rod D another pinion 23^b is mounted. These pinions engage with the rack-teeth 17 on the racks 15 of the adjusting-plates C.

The extremities 27 of the sieve-supporting rod D are threaded, and one end, that at which the pinion 23 is located, is provided with a nut 25, adapted when tightly screwed to engage with the pinion 23, while at the opposite threaded end of the sieve-supporting rod D a nut 26 is located, adapted for engagement with the pinion 23^a. Ordinarily the sieve-supporting rod D is passed through the upper apertures 22 in the locking-plates C' at the portions of the shoe mentioned, as shown in Fig. 5; but it will be understood that the said sieve-supporting rod D may be passed through any one of the lower apertures 22^a in the aforesaid locking-plates; but the principal purpose of the lower aperture 22^a in the locking-plates is to receive any plain rod threaded on each end, adapted for the reception of a thumb-nut or its equivalent, and such rods so placed are intended to carry one or more additional sieves. Ordinarily the added rod is used in the upper holes of the locking-plates C' at all times, and by loosening the nuts carried by the lower rod when it is used the adjustment of the sieves is proceeded with in the manner above explained.

At or about the central portion of the sieve B a foot 28 is secured in any approved manner, (shown best in Figs. 3 and 5,) which foot

extends beneath the aforesaid sieve-supporting bar D, enabling the sieve to be readily supported by the said rod and yet to have longitudinal movement in the shoe.

In the adjustment of the sieve at the deeper end of the shoe A it is simply required to loosen the nut 25 and shift the rod D slightly toward the opposite nut 26, which need not be attended to, the object being by this movement of the rod to disconnect the locking-plates from their locking adjustment with the adjusting-plates, so that at such time the hand-wheel 24 may be turned and the pinions 23 and 23^b, traveling on the racks 15 of the adjusting-plates, will cause this delivery end of the sieve to be raised or lowered as far as may be required. When suitable adjustment has been reached, by simply tightening the nut 25 against the pinion 23, having the wheel 24 attached, the locking-plates are again brought in engagement with the adjusting-plates, and the rods D are held in their adjusted position.

With reference to the support for the sieve at the receiving or shallower end of the shoe a rod D' is employed which corresponds to the rod D, and the adjusting devices are duplicated. The rod D' is operated in the same manner as the rod D; but the adjusting-plates at the shallower end of the shoe are of less length than those at the deeper or discharge end. Another difference, however, resides in the fact that the receiving or shallower end of the sieve B instead of being supported upon its rod D' is pivotally carried by the said rod D' through the medium of suitable knuckles 29, through which the said rod D' passes, as is clearly shown in Fig. 4.

The scales c are used in the following manner: When an adjustment has been made at one end of the shoe—the deeper end, for example—and the pointers 22^b on the locking-plate C are brought opposite the figure "5" on the scale over which they travel, a corresponding adjustment for the sieve may be made at the shallow end of the shoe by carrying the pointers 22^b at that end downward to a corresponding figure on the scale on the adjusting-plates at the said shallower ends. It will be understood, however, that independent adjustment of the sieve may be made at either end of the shoe and that all the adjustments are made from one side of the shoe, so that the adjustments are under the complete control of a single operator.

I desire it to be understood that the wheels 24 for operating the rods D and D' are at that side of the shoe at which the operator usually stands and that on the adjusting-plates at the opposite side of the shoe the scales c are not required, nor is it required that the pointers 22^b shall form a portion of the locking-plates at the latter-mentioned side of the shoe.

Having thus described my invention, I

claim as new and desire to secure by Letters Patent—

In devices for adjusting the sieves in threshing-machines, the combination with a shoe provided with opposing slots in its sides at its end portions, adjusting-plates secured to the outer faces of the slotted portions of the shoe, which plates are provided with slots corresponding to those in the shoe, being also provided with corrugations upon their outer faces; a longitudinal rack extending from one side edge of each adjusting-plate, a depression being produced at the opposing side edge of each adjusting-plate, and scales upon said depressed surfaces, locking-plates in engagement with the adjusting-plates, being movable thereon and provided with a series of vertically-alining apertures and corruga-

tions upon their inner faces, together with guide-lugs which enter the slots in the adjusting-plates, extending over the said scale-surfaces, of rods passed through certain of the openings in the locking-plate, a sieve pivotally connected with one rod and provided with an open bracket upon its under face receiving the other rod, pinions secured to the rods engaging the said racks, and hand-wheels secured to sundry of the pinions, as described.

In testimony whereof I have signed my name to this specification in the presence of two subscribing witnesses.

JOHN A. STEELSMITH.
